PNEUMATIC PROTECTOR FOR ATHLETES

Original Filed June 16, 1924

Inventor
George E. Mott.

By Walter W. Burns
Attorney

UNITED STATES PATENT OFFICE

GEORGE ERNEST MOTT, OF MAIDEN, MASSACHUSETTS, ASSIGNOR TO WALTER W. BURNS,
OF WASHINGTON, DISTRICT OF COLUMBIA

PNEUMATIC PROTECTOR FOR ATHLETES

Application filed June 16, 1924, Serial No. 720,438. Renewed September 20, 1929.

This invention relates to pneumatic athletic protectors for the upper portion of the body and is particularly adapted for use by foot ball players.

5 In playing the game of foot ball, the greatest number of injuries, as the game is played at the present time are about the upper portion of the body. These injuries are principally of three kinds:—broken collar bones, 10 separation of the bones at the joint between the humerus and the shoulder blade and injury to the joint between the collar bone and the shoulder blade.

Various kinds of pads have been made to 15 give protection to these parts of the body, but these have been of little or no protection unless made so heavy and bulky that their weight and bulk interfered with the movements of the wearer.

20 The primary purpose of my invention is the provision of an improved pneumatic body protector which will be of such construction as to practically eliminate the danger of the injuries above mentioned and which will be 25 light and will not interfere with the movements of the wearer.

Another purpose of my invention is the provision of a pneumatic body protector having inflated means embodied in a fabric body 30 portion, the latter fitting the shoulder and back of neck and the former being secured to the body portion of the protector and covering, when in place, the top of the shoulder blades, shoulders and collar bones.

35 Referring to the drawing wherein I have illustrated a preferred embodiment of my invention,

Fig. 1 is a plan view of my preferred embodiment,

40 Fig. 2 is a side view of Fig. 1,

Fig. 3 is a cross section on the line 3—3 of Fig. 1,

45 Fig. 4 is a perspective view showing the protector in place on a foot ball player, the neck and shoulder harness being omitted for the sake of clearness.

Similar parts are designated by the same reference characters throughout the views.

50 10 designates the body portion of the protector which may be of any suitable material

as drilling. This body portion is preferably made of two thicknesses and stitched in a manner to provide for the inflated means to be described. The general shape of the body portion is U-shape, the inside edge 11 thereof 55 being of a size to fit the neck of the player when the protector is in place. Suitable fastening means such as eyelets 12 and lace 13 are provided to secure the protector about the neck.

60 A suitable line of stitching 14 is provided to fasten the two thicknesses of the body portion 10 together and, with the outer stitched edge 15, to form a pocket 16 to receive the pneumatic means 17 which is intended to be 65 inflated to the desired pressure and which in the present embodiment of my invention is made in one piece and extends about the neck of the wearer and in position to cover the tops of the shoulder blades, the joints at the 70 shoulders and the collar bones in front. At suitable places on the outer edge of the protector are attached arm loops 18 which carry rubber tubes 19 to contact with the body under the arms.

75 A suitable means by which the pneumatic means is inflated, is provided as shown by the tube 20 on Figs. 1 to 3. By means of a suitable pump applied to the tube 20, the pneumatic means may be inflated to the desired 80 pressure after which the end of the tube 20 may be bent and secured in a well known manner. The outer edge of the protector is preferably bound with a tape or other suitable binder 21 to prevent fraying.

85 The forward or front portion of the pneumatic means and also that portion of the pneumatic means directly over the shoulders are preferably made wider than the rear portions since these front and side portions cover the points which require the greatest protection.

90 The arm loops 18 with the tubes 19 enclosing the same, provide a comfortable means for holding the outer portions over the shoulders. Since the inner edge 11 is of such a length that it fits neatly but not tightly about the neck, the whole protector is prevented 95 from having a forward, rearward or sideward movement.

After the protector is in place, the harness, with the usual shoulder-projecting cup shape members, is put in place, after which the jersey is put over all. With such a protector, 5 greater protection to the body is obtained, at the same time obtaining greater freedom with less weight.

While I have described and shown an embodiment of my invention, I desire to have 10 it understood that the showing is merely illustrative and that modifications and changes may be made without departing from the spirit of my invention and within the scope of the appended claims.

15 Having described my invention, what I claim and desire to secure by Letters Patent is:—

1. An athletic protector comprising a body portion having an edge of a shape to fit the 20 neck of the wearer, a continuous pneumatic means secured to the body portion in a spaced position from the neck-engaging edge and in position to lie above and slightly outside the shoulder and collar bone of the wearer.

25 2. An athletic protector comprising a body portion having an edge of a shape to fit the neck of the wearer, and a continuous pneumatic means spaced from the neck engaging edge and secured to the body portion in position to extend over and protect the shoulder and collar bone of the wearer.

30 3. An athletic protector comprising a body portion having an edge of a shape to fit the neck of the wearer, a narrow continuous 35 pneumatic means secured to the body portion and spaced from the neck-engaging edge in position to extend over and protect the tops of shoulder blades, shoulders and collar bones of the wearer.

40 In testimony whereof I hereunto affix my signature.

GEORGE ERNEST MOTT.
